FOLDING LADDER

Stephen E. Burke, Evanston, Ill.

Application April 15, 1933, Serial No. 666,377

9 Claims. (Cl. 228—23)

This invention relates to ladders and particularly to extension ladders of the foldable type.

In folding ladders as at present constructed, difficulty has been found in keeping the sections 5 positively in extended position when in use and also in keeping the folded sections lying against one another when the ladder is in the folded or carrying position.

The primary object of this invention is the provision of an improved folding ladder having substantial hinge means for holding the sections in extended position.

Another object of the invention is the provision of hinge means for folding sections of a folding 15 ladder which are provided with an improved positively locking means for holding the sections in extended position.

Another and further object of the invention is the provision of a single locking means for a folding ladder which in one position locks the sections in open or extended position and in another locks the sections in folded position.

Another and still further object of the invention is the provision of a single locking member to 25 hold sections of a folding ladder in either extended position or folded position and so constructed that when it is moved from holding the sections in folded position it is ready to automatically function to hold them in extended position when and as soon as they are extended.

Other and further objects will be apparent to those skilled in the art from a reading of the complete specification and claims.

Referring to the drawings wherein I have illustrated an embodiment of my invention,

Figure 1 is a fragmental view of two stiles of adjacent sections of a ladder showing my improved hinge connection, the ladder sections being secured in extended position.

Figure 2 is a view similar to Figure 1, but showing the swinging locking means in a released position, the ladder sections being moved from the extended position toward folded position.

Figure 3 is a view from the left in Figure 1.

Figure 4 is a view similar to Figure 3, but showing the locking means in released position.

Figure 5 is a reverse view of the hinge member only illustrated in Figure 1, the locking means being in locked position.

Figure 6 is a fragmental view of the ends of three sections when in folded position.

Figure 7 is a view similar to Figure 6 showing the free end of an end section swung clear after being released or in a position just before it is 55 completely folded.

Figure 8 is a view of another form of my invention similar to the showing in Figure 1, but showing a coil spring in place of the leaf spring of the previous views.

The same reference characters refer to the same 60 or similar parts throughout the various views of the drawings.

In carrying out my invention it has been considered desirable to provide a hinge and securing means which would provide the maximum 65 strength and would be ready to function, at all times.

The construction of the ladder sections per se as used with my invention, are conventional. A very convenient size for many purposes is a ladder 70 11 feet long divided into three 44 inch sections.

In Figures 1 and 2 are illustrated two adjacent stiles showing the hinge connections on the inside of the stiles. In order to prevent accidental displacement of the holding means, I place the working parts on the inside of the stiles as in this position they are protected against accidental displacement by everything except the body of the user. The stile 10 of the upper section of the 75 ladder has a hinge section 11 secured thereto by suitable screws or rivets 13. The stile 14 of the relatively lower section of the ladder has a corresponding hinge section 15 which is pivotally connected to the hinge section 11 at their edges 80 by a pivot member 16. The pivot member 16 is preferably so placed that its center is in the line of the edges of the stiles 10 and 14.

The adjacent ends of the hinge sections 11 and 15 overlap in a way to furnish coating complementary portions to provide securing means 90 to give a proper stiffness when the ladder sections are secured in extended position. To bring about this result, I have provided a pressed-out tongue 17 which extends into the path of movement of the lower edge of the upper hinge section 11.

At the edges of the plates 11 and 15 opposite to the pivot 16, are coating complementary notches 18 and 19 whose shoulders 18^a and 19^a 100 coact with a holding member, to be described, to hold the ladder sections in extended position. In the form illustrated, the notches 18 and 19 are so placed that they register when the lower edge of the hinge section 11 rests upon the tongue 17. 105

A locking member 20 is mounted upon an arm 21 which is pivoted at 22 to one hinge section as the upper section 11. In the form illustrated in Figures 1 to 7, there is a cam end 23 on the end of the pivot 22 opposite to the arm 21. This cam 110

end has two flat surfaces which are for engagement with a spring 24. One of these cam surfaces 23^a when in engagement with the spring 24, resiliently holds the locking member 20 in the notches 18, 19. When this locking member 20 is in the notches 18, 19, the cooperation with the notch shoulders 18^a, 19^a and the locking member 20, together with the coaction between the hinge section 11 and the tongue 17 and the pivot pin 16 with the hinge sections 11, 15, secures the hinge sections 11, 15 in rigid extended position.

It is to be noted that the upper corner of the hinge section opposite the section upon which the locking member 20 is mounted, has a cut away corner as at 15^a. The purpose of this is to permit the locking member 20 to ride up over the corner 15^a and snap into the notch 19 as the ladder sections are brought to extended position.

As already indicated, the locking member 20 not only holds the two adjacent ends of two ladder section stiles in extended position, but this locking member 20 also serves to hold one of the two adjacent sections and the free end of a third section in folded position. This I have illustrated 25 in Figures 6 and 7. In these figures, the stiles 10 and 14 are shown as the middle and left sections. At the right is the free end 26 of a stile of a third ladder section, the opposite end (not shown) being connected to the stile 10 as already 30 described for the hinge connection between the stiles 10 and 14. Unless some means are provided to keep the relatively free ends close to each other when the ladder is folded, the ladder is difficult to handle and transport. To secure 35 the stile 26 in place when folded, I provide a plate 27 on the inside of the stile 26 in a position so that the detent means 25 will be in position to be engaged by the locking member 20 when the latter is in a position away from the notch 18. When so engaged the cam end member 23 is engaged 40 on its flat surface 23^b by the spring 24.

Assuming the parts to be in the position as illustrated in Figure 6, the free sections are released by releasing the locking members 20 from the detent means 25. As the locking member 20 is moved, the spring 24 loses contact with the flat surface 23^b and contacts with the flat surface 23^a.

The locking member 20 is drawn by the spring 50 24 into the notch 18.

As the ladder sections are extended, the locking member 20 rides up over the cut away edge 15^a and as the complementary notches 18, 19, register, the locking member 20 drops into place 55 and holds the ladder sections in extended position. To release the sections to fold the ladder, a reversal of the operations is made, the locking member 20 being left in a locked position relative to the detent means 25.

60 In the form shown in Figure 8, the construction of the parts is similar except that a coil spring 124 replaces the cam 23 and the spring 24. The operation is similar to that already described and needs no further description.

65 While I have described and shown embodiments of my invention in detail, I desire to have it understood that these are merely illustrative and that modifications and changes may be made without departing from the spirit of the invention 70 and within the scope of the appended claims.

Having described my invention what I claim and desire to secure by Letters Patent is:—

75 1. Hinge means for folding ladders comprising two relatively movable members, pivot means for securing the members together at their edges,

coacting open notches at the edges opposite to the pivots and extending into the bodies of the movable members and a holding device engaging the notches to hold the movable members in extended position.

80

2. Hinge means for folding ladders comprising two relatively movable members, pivot means for securing the members together at their edges, each movable member having an open notch extending into its body portion and coacting with a notch in the other member and pivoted holding means for registering with the notches to hold the movable members in extended position.

85

3. Hinge means for folding ladders, comprising two relatively pivoted members, pivot means for securing the members together at their edges, each movable member having overlapping portions relative to the other and each having an open notch extending into its body portion and complementary to the other notch, and each 95 having complementary stop means to limit relative movement in one direction and a pivoted holding means for engaging the notches to hold the pivoted members against movement when in extended position.

100

4. Hinge means for folding ladders, comprising two relatively pivoted members, pivot means for securing the members together at their edges, each movable member having an open notch extending into its body portion and complementary 105 to the notch of the other movable member and each member having complementary stop means to limit relative movement in one direction and a spring pressed pivoted holding means for engaging the notches to cooperate with the stop 110 means to hold the pivoted members against movement in either direction when the folding ladder sections are in extended position.

105

5. A folding ladder having a series of sections, pivots for pivoting adjacent sections together and means for securing the sections in extended relation when in one position and for securing the free end of an adjacent section in folded position when in another position.

115

6. A folding ladder having a series of sections, pivots for pivoting the adjacent sections together and a securing means pivotally mounted adjacent one of the pivots to at will hold the pivoted sections in extended position or to engage the free end of another adjacent section to hold the latter in folded position.

120

7. A folding ladder having a series of sections, hinge plates secured to adjacent sections and having complementary shoulders, a pivot for pivotally securing the plates together at their 130 edges and a swinging member engaging the complementary shoulders of the plates to hold the adjacent ladder sections in extended position when the swinging member is in one position and to hold the free end of another adjacent section 135 when the swinging member is in another position.

130

8. A folding ladder having a series of sections, hinge plates secured to adjacent sections and having complementary shoulders, a pivot for pivotally securing the plates together at their edges, a swinging member engaging the complementary shoulders of the plates to hold the adjacent ladder sections in extended position when the swinging member is in one position and to 140 hold the free end of another adjacent section when the swinging member is in another position, and resilient means tending to hold the swinging member in either of its holding positions.

145

9. A folding ladder having a series of sections, hinge plates secured to adjacent sections and having complementary shoulders, a pivot for pivotally securing the plates together at their edges, the plates having complementary means for limiting relative movement in one direction and having complementary notches with shoulders, and a swinging member engaging the complementary shoulders of the plates to hold, with the limiting means, the adjacent ladder sections in extending position when the swinging member is in one position and to hold the free end of another adjacent section when the swinging member is in another position. 80
